(57) **CLAIM**

I claim the ornamental design for a microphone clip, as shown and described.

DESCRIPTION

FIG. 1 is a perspective view of a microphone clip.

FIG. 2 is a side view of the microphone clip of FIG. 1.

FIG. 3 is an opposite side view of the microphone clip of FIG. 1.

FIG. 4 is a front view of the microphone clip of FIG. 1.

FIG. 5 is a rear view of the microphone clip of FIG. 1.

FIG. 6 is a top view of the microphone clip of FIG. 1; and, FIG. 7 is a bottom view of the microphone clip of FIG. 1. In the drawings, the evenly-spaced broken lines disclose environmental subject matter only and form no part of the claimed design. The alternating dash-dot-dash lines represent boundaries of the claimed design, the claimed design extending to the boundary but not including the boundary. The dash-dot-dash lines provide a boundary around a claimed finger loop portion of the microphone clip.
